1,557,626

UNITED STATES PATENT OFFICE.

PETER SWANSON, OF ELY, MINNESOTA,

RAILROAD SWITCH.

Application filed February 16, 1925. Serial No. 9,370.

To all whom it may concern:

Be it known that I, PETER SWANSON, a citizen of the United States, residing at Ely, in the county of St. Louis and State of Minnesota, have invented certain new and useful Improvements in Railroad Switches, of which the following is a specification, reference being had therein to the accompanying drawing.

10 This invention relates to switch signaling devices and has special reference to a novel arrangement of target and lamp for railroad switches.

15 The principal object is to provide a more efficient and reliable signalling device for such switches.

Another object is to provide means whereby to prevent accident in the event of the switch being left unlocked even though not 20 thrown to dangerous position.

Other objects and advantages will appear in the further description of the invention.

Referring now to the accompanying drawing, forming part of this application, and in 25 which like reference characters indicate like parts:

Figure 1 is an elevation of the switch target, or signalling device in an all clear position;

30 Figure 2 is a similar view illustrating the target and lamp signalling that the siding is open, or danger for the main line;

Figure 3 is a similar view showing the danger signal in the event of the switch being 35 left unlocked even though turned for all clear position for the main line;

Figure 4 is a top plan view of the lamp target, showing the lamp in dotted lines; and

40 Figure 5 is a perspective view of the main target.

At 1 is illustrated an ordinary switch stand, provided with an operating lever 2, pivoted as at 3, to the supporting links 4, and by which the switch is thrown, the lever 2 being pivoted as at 5 upon the switch stock 6, which is rotated when the lever is raised subsequent to the unlocking of same and which may be accomplished in various 50 ways.

In the improved form of switch the locking lug 7, which is usually single, I prefer to make double, forming a guide in which the target operating rod 8 is engaged either 55 when held by the padlock 9 or free therein when the target drops.

This operating rod 8 extends upwardly to a bracket 10 securely attached to one wing of the target, and there are two of these brackets 10 spaced apart one upon either 60 side of the target staff 0.

These brackets are held in position on the staff by there being a through hole in the staff and a bolt indicated at 11 which passes through the brackets and the staff, the bolt 65 carrying upon either side of the staff a gas pipe sleeve 12 which is cut at one end to fit the corner angle of the staff and at the other end extending within holes sufficiently large for such purpose in the brackets 10, so that 70 the head of the bolt at one end and the nut at the other end impinge against the sleeves 12 in preference to the brackets 9 which permits of the latter rotating freely upon the ends of the sleeves, though not separable 75 therefrom so long as the bolt is held tightly in position; this making a very practical and substantial manner of mounting the target on the staff.

The rod 8 is pivotally attached as at 13, 80 spaced horizontally from the pivotal mounting of the brackets, so that any movement of the rod tends to oscillate the brackets upon their support.

Now the target comprises a peculiarly 85 shaped three-winged member composed of the angularly disposed normally vertical wings 14 and 15, united by the intermediate horizontal wing 16. The wing 16 is rigidly mounted upon the brackets 10 so that the entire target is rockable with the brackets. So long as the rod 8 is in its uppermost extended position with the padlock 9 holding same in such position, the brackets 10 with the target will be horizontally disposed in its 90 95

all clear position such as shown in Figure 1 of the drawings; but should the padlock 9 be removed, thus disconnecting the rod 8 from the lugs 7 and allowing same to fall, the target will drop to the position shown 100 in Figure 3 regardless of whether the switch staff is rotated or not, thus indicating a danger signal, as both sides of the wing 16 of the target carry a red bull's eye as does also the wing 15, while the wing 14 carries a 105 white or safety bull's eye upon both sides. Now should the switch be subsequently turned as it can only be after the removal of the lock just described the danger signal still continues as shown in Figure 3, and 110 even after such turning of the switch for the siding, the rod 8 being raised, the danger

signal still is in evidence as shown in Figure 2, for the all clear wing 14 can be viewed only edgeways. Should the switch by any means be left partly thrown it is quite obvious that the danger signal on both the wings 15 and 16 would appear at an angle to either line of traffic, thus insuring positively against any misunderstanding of the signal. On the back of the wing 14 is attached a resilient spring member 17 so that when the target is up against the staff the same will engage the staff and prevent rattling of the target thereagainst.

Above the target just described, the staff 15 is squared oppositely to that portion below the target, and has fastened thereto, as at 18, two cross arms 19 which extend upon opposite sides of the staff and support upon their ends, as at 20, the thin metal shields 21, one 20 upon either side of the staff.

One terminus of these substantially U-shaped shields is semi-circular in shape as at 22 to act as a shield behind which the colored glass 23 of the danger signal arm 24 is hid when the signal arm is inactive; while the opposite ends 25 of the shield members act as a support for the through horizontal shaft 26 which pivotally supports the danger signal arms 24, they being composed of a single piece of thin metal of general U-shape and mounted upon the shaft as clearly seen in Figure 4 of the drawings. Protruding rearwardly of the horizontal portion 27 of the signal arm structure are spaced lugs 28 into which is pivotally connected as at 29 the signal arm operating rod 30, the opposite end of said rod being pivotally connected as at 31 to one of the brackets 10, so that as the target, comprising the wings 14, 15 and 16, is operated, the signal arms 24 will likewise be operated. That is to say when the target is in all clear position as shown in Figure 1 of the drawings, the signal arms carrying their danger bull's eye will be hid behind the shield 22 so that the lamp 31 which is

mounted in the usual way on the extreme upper end of the staff will show all clear as a night signal, while, when the target is dropped, showing danger, the signal arms 24 will be in raised position as shown in Figure 3 and the lamp will also show danger by the appearance of the danger bull's eye before the light therein. Furthermore, as is evident, if the staff is turned by the turning of the switch to danger position, then the danger or red lights of the lamp will show in the usual way.

From the foregoing it is evident that I have provided a simple and dependable form of target for a railroad switch which not only indicates the position of the switch but any tampering therewith, and one automatically operable in conjunction with the lamp of a switch so as to afford equal efficiency at night.

Having thus described my invention, what I claim and desire to secure by Letters Patent is:

1. A gravity target for railroad switch stands comprising three angular rigidly united target wings, substantially as described.
2. The combination with a railroad switch stand, of an automatically gravitating target therefor comprising three angular rigidly united target wings.
3. The combination with a railroad switch stand carrying an independently adjustable target thereupon and lock therefor, of means whereby unlocking of the switch automatically operates the target.
4. The combination with a railroad switch stand of the type described carrying signalling means and locking means for the switch, of means whereby the unlocking of the switch automatically operates the signalling means.

In testimony whereof I hereunto affix my signature.

PETER SWANSON.
